UNITED STATES PATENT OFFICE.

WILLIAM O. ABBOTT, OF KITTANNING, PENNSYLVANIA.

DESIGN FOR AN ENVELOP.

SPECIFICATION forming part of Design No. 31,725, dated October 24, 1899.

Application filed September 9, 1899. Serial No. 730,031. Term of patent 14 years.

To all whom it may concern.

Be it known that I, WILLIAM O. ABBOTT, a citizen of the United States of America, residing at Kittanning, in the county of Armstrong and State of Pennsylvania, have invented a certain new and useful Design for an Envelop, of which the following is a specification, reference being had therein to the accompanying drawings.

10 This invention relates to a certain new and useful design for envelopes, and has for its object to provide a design of novel and original shape.

As shown in the accompanying drawings, 15 the design consists in an envelop the novel outline and configuration of which will be more particularly described and specifically pointed out.

In describing the invention in detail reference is had to the accompanying drawings, forming a part of this specification, wherein like numerals of reference indicate corresponding parts throughout both views, in which—

25 Figure 1 is a front view of my design for an envelop. Fig. 2 is a rear view of the same.

In the drawings, 1 indicates the top or upper horizontal line of the envelop; 2, the one side or end which is at right angles to the top or upper horizontal line; 3, the base or lower horizontal line, which extends at right angles to the side or end 2 and is parallel with the top or upper horizontal line 1. 4 indicates the opposite side or end connecting the top line 1 by an obtuse angle and base-line 35 3 by an acute angle, the said side or end 4 extending diagonally between the lines 1 and 3, as shown.

5 denotes the upper flap of the envelop, which is substantially triangular in outline, 40 and 6 the lower flap of the same outline.

Having thus fully described my invention, what I claim as new, and desire to secure by Letters Patent, is—

The design for an envelop, substantially as 45 shown and described.

In testimony whereof I affix my signature in the presence of two witnesses.

WILLIAM O. ABBOTT.

Witnesses:

JOHN NOLAND,

WILLIAM E. MINOR.
